UNITED STATES PATENT OFFICE.

MAXIME ALFRED LAUBEUF, OF PARIS, FRANCE.

SAFETY-WEIGHT FOR SUBMARINE VESSELS.

1,035,021.

Specification of Letters Patent. Patented Aug. 6, 1912.

Application filed April 20, 1908. Serial No. 428,149.

To all whom it may concern:

Be it known that I, MAXIME ALFRED LAUBEUF, a citizen of the Republic of France, residing at Paris, in the Department of the Seine, France, have invented 5 certain new and useful Improvements in Safety-Weights for Submarine Vessels, of which the following is a specification.

My present invention pertains to improvements in submarine vessels, and has reference more particularly to the arrangement and manipulation of safety weights.

The invention is illustrated in the annexed drawings, wherein:

15 Figure 1 is a longitudinal sectional view of a submarine vessel showing my invention applied thereto; Fig. 2 a vertical sectional view of a portion of the hull, showing the weight and the operating mechanism on a somewhat enlarged scale; Fig. 3 is a horizontal sectional view, taken on the line 3—3 of Fig. 2; Fig. 4 a diagrammatic view, showing a modified arrangement, whereby the weights may be released at any desired 25 point or automatically released when the vessel has attained a predetermined depth; Fig. 5 a detail view showing a modified arrangement of the valve-actuating mechanism; and Fig. 6 a detail sectional view of 30 the valve used in conjunction with the primary form of the apparatus.

The main object of the present invention is to provide a system of safety weights which may be manipulated from a single 35 point to instantly release either weight, or both, as occasion may require.

A further object of the invention is to provide, in conjunction with the manually-operated releasing mechanism, an automatically-operated releasing mechanism, which when the vessel has attained a predetermined depth will automatically release the weights. The arrangement of the weights in the hull is such that they may be 45 released notwithstanding the fact that the vessel may be grounded or resting upon the bottom at the particular point or points where the weight or weights are located. The arrangement contemplates the use of at 50 least two weights, one fore and the other aft, with means for releasing one or the other or both of said weights.

Referring to the construction shown in Figs. 1 to 3 of the drawings, A denotes the hull of the vessel, shown merely in outline 55 for the purpose of illustration. B design-

nates the weight which is placed fore, and C the corresponding weight placed aft. A pocket or recess D is formed in the hull for the reception of each weight, the pocket being of a height greater than that of the weight and the weight-sustaining mechanism, which is located in the upper portion of the pocket. The pocket will be made in the form of a truncated cone or pyramid, 60 and the weight will have the same general shape but will be somewhat smaller than the pocket, in order that when suspended within the pocket the bottom of the weight may be at a point higher than the general line 65 of the bottom of the hull. The weight is suspended above the bottom for the purpose of allowing said weight to be disengaged when the vessel is resting upon the ground in line with the pockets in which the weight is located. The upper end of each weight is provided with a ring or eye E, into which passes the free end of a hook or L-shaped member F, the latter being secured upon or rigidly affixed to a horizontally-disposed 70 rocker-shaft G, which extends through a stuffing-box H, secured to one side wall of the pocket. The outer end of the shaft will by preference be supported in a bearing I (Fig. 3), secured to that wall of the pocket 75 which is opposite the wall carrying the stuffing-box. To the inner end of the shaft is secured an arm J, the free or outer end of the arm (when the weight is in its elevated position) extending beneath a pin or piston-rod K, which latter is secured to and movable with a piston L mounted in a cylinder M. So long as the piston-rod is projected 80 out and extends over the arm J, as shown in the drawings, the weight will be held in its 85 suspended position.

As will be seen upon reference to Fig. 1, there is a piston and cylinder for each weight, and pipes N N' extend from the respective pistons to a valve mechanism O, 100 by which the admission of compressed air or other fluid under pressure from a pipe P to either of said pipes N or N' is controlled. Said pipes discharge into the cylinders in front of the pistons, so that compressed air or other agent passing into the cylinders 105 will force the pistons rearwardly and withdraw the rods K from over the arms J, thereby permitting the rocker-shafts to rotate and the weights to slip off the hooks F. In Fig. 6 I have shown a valve arrangement 110 whereby either weight may be released, or

both released simultaneously. In said figure, P denotes a pipe leading to a chamber P', exit from which to the pipes N, N' is controlled by the two valves P² and P³, normally held closed by springs. An actuating lever P⁴, fulcrumed in a sliding block P⁵, underlies the downwardly-projecting valve-stems, and by rocking it in one or the other direction, one or the other valve may be opened, as desired. By operating a screw P⁶, mounted in the yoke P⁷ of the valve-casing, lever P⁴ will be bodily raised, and both valves will be simultaneously opened, and as a consequence both weights likewise released. It is conceivable, of course, that separate valves may be employed to control the supply of compressed air to the two cylinders, but in order that the apparatus may be under the control of the navigator the valves should be located at a single point. While a single weight only is shown at each end of the vessel, a plurality of weights may be employed at each end, but as this is mere duplication it is not deemed necessary to illustrate the same. The angle of inclination of the side walls of the pocket in which the weight is normally housed is such that when the weight is released it will pass out of the pocket under the action of gravity, this notwithstanding the fact that the vessel may be in an inclined position.

In Fig. 4 is illustrated a modified arrangement, under which the weights may be either released manually or automatically when the vessel has reached a predetermined depth. In said figure the weight and suspending means therefor are similar to those shown in the previous figures, and are designated by the same reference letters. Opening into the cylinder M at the lower end thereof to one side is a pipe N', controlled by the valve O, as in the former construction. A second pipe Q also opens into the lower end of the cylinder, said pipe terminating in a valve-chamber R, in which is mounted a valve S that normally closes the port or passage leading to the pipe Q. Air or other fluid under pressure enters the valve-chamber through a pipe T; which may be a branch of the pipe that conveys the compressed air to the pipe N. Valve S is mounted upon a stem U, provided with a quick pitch thread V, which works in a suitable bearing secured in the valve-casing. To the outer end of the valve-stem U is secured an arm W, which in turn is pivotally connected by a link W' to the lower end of the solenoid X of a magnet Y. The winding of the magnet is included in a normally open circuit which may be closed by a solenoid switch Z, which latter is in a normally open circuit A'. Included in the circuit A' is a gage, comprising an adjustable contact member B', which may be set to any desired point upon the scale, and a needle C'.

Said needle is actuated indirectly by the pressure of the water, which enters a Bourdon tube D', to which is attached a rack F', said rack meshing with a pinion G' made integral with or secured to an internal gear H', which in turn meshes with a pinion I', to which the needle is attached. The rack is held to the pinion by a roller J'. It will, of course, be understood that the pinion I' will be insulated, so that until the needle C' contacts with the member B' the circuit A' will be open. The contact member B' may be adjusted to close the circuit at any predetermined point, and as will be readily appreciated when the vessel reaches a given depth the needle will close the circuit A', thereby energizing the magnet E' and actuating the solenoid switch Z to close the circuit in which the magnet Y is located. A relatively weak current is all that it is necessary to employ in conjunction with the gage and the magnet E'. A heavy current, however, will be passed through the line which controls the action of the magnet Y and its solenoid. The upward movement of the solenoid X will, through the connections hereinbefore described, rotate the valve-stem U and unseat the valve S, permitting air to pass through the pipe Q and move the piston inwardly into the cylinder M. This will have the effect of releasing the weights in the manner hereinbefore described.

It will be readily appreciated that in so far as the connections for actuating the valve are concerned they may be changed without departing from the spirit of the present invention. For instance, in Fig. 5 the valve-stem is shown as provided with a worm-wheel F', actuated by a worm formed upon the end of the shaft G' of a motor H'. Said motor will occupy the same relative position as the magnet Y and its solenoid, which are in effect a motor. It will likewise be understood that the pipe Q may be provided with a branch or lateral extending to the weight located in the other pocket formed in the vessel.

In so far as the generic invention is concerned, any means for releasing the weights instantly may be employed, though the arrangement shown will be found efficacious in practice.

Having thus described my invention, what I claim is:

1. A submarine vessel provided with water-tight pockets or recesses in its hull, said pockets being placed fore and aft; a weight located in each pocket; and means under the control of the navigator for wholly freeing and releasing at will either of said weights or, simultaneously, both of said weights, and permitting the same to pass freely out of their respective pockets.
2. A submarine vessel provided with

pockets located fore and aft; a weight suspended within each of said pockets, the bottom portion of the weight being at a point above the line of the bottom of the hull; and means under the control of the navigator for releasing either of said weights, or both of said weights simultaneously at will.

3. A submarine vessel provided with pockets fore and aft; a weight mounted in each of said pockets, the bottom of the weight standing at a point above the bottom of the hull of the vessel; and means located amidship for releasing one or the other or both of said weights and permitting the same to pass out of the pockets.

4. A submarine vessel provided with pockets located in the lower portion thereof fore and aft; a weight mounted in each of said pockets, the weight being of such height that its bottom stands at a point above the bottom of the hull of the vessel; means for sustaining said weights in the pockets; and means under the control of the navigator for releasing either of said weights or both of them simultaneously at will.

5. A submarine vessel provided with a pocket located in the bottom portion thereof; a weight, said weight being of such height that the bottom thereof stands at a point considerably above the bottom line of the hull; a rock-shaft extending into the pocket; a hook-shaped member carried by the rock-shaft; an eye upon the upper portion of the weight adapted normally to pass over the hook-shaped member; means for normally holding the rock-shaft against motion; and means for releasing the rock-shaft so as to permit it to move and disengage the hook from the eye and the weight.

40 6. A submarine vessel provided with pockets fore and aft, each of said pockets having inclined side walls; a weight mounted in each of said pockets, said weights being of the same general form as the pockets and being of a height materially less than that of the pocket; a rock-shaft extending into each of said pockets; a hook carried by

each shaft; an eye upon each of said weights adapted to engage a hook; an arm rigidly secured to the inner end of the rock-shaft 50 within the hull of the vessel; a pair of cylinders; a piston mounted in each of said cylinders; a piston-rod extending outwardly from each of the cylinders, the piston-rods passing over the respective arms; a source of 55 fluid pressure; pipes leading therefrom to the cylinders; and a valve for controlling the passage of the fluid to said cylinders, whereby one or both of said weights may be released by the simple manipulation of the 60 valve.

7. A submarine vessel provided with a pocket or recess in its hull; a weight located in the pocket; means under the control of the navigator for releasing the weight and 65 permitting the same to pass out of the pocket while the vessel is at any point of submergence; and automatic means for releasing the weight when the vessel has reached a predetermined depth.

8. A submarine vessel provided with a pocket or recess in its hull; a weight located in the pocket; mechanism under the control of the navigator for releasing the weight; a depth-gage; and means controlled by said 75 gage for actuating the weight-releasing mechanism when the vessel has reached a predetermined depth.

9. A submarine vessel provided with a pocket or recess in its hull; a weight located 80 therein; fluid-pressure mechanism under the control of the navigator for releasing the weight when desired; and independent automatic means for throwing the fluid-pressure mechanism into operation when the vessel 85 has reached a predetermined depth.

In testimony whereof, I have signed my name to this specification in the presence of two subscribing witnesses.

MAXIME ALFRED LAUBEUF.
